UNITED STATES PATENT OFFICE.

MARGARET H. BROSNAN, OF WASHINGTON, DISTRICT OF COLUMBIA.

VANITY-CASE FOR PERSONAL WEAR.

1,400,139.

Specification of Letters Patent. Patented Dec. 13, 1921.

Application filed August 27, 1920. Serial No. 406,349.

To all whom it may concern:

Be it known that I, MARGARET H. BROSNAN, a citizen of the United States, residing at Washington, in the District of Columbia, 5 have invented new and useful Improvements in Vanity-Cases for Personal Wear, of which the following is a specification.

My present invention has for its object the provision of a vanity case for personal 10 wear, characterized by its simulation of a rose or other flower and by its construction which lends itself to the attachment of the device to the corsage of a lady's dress and to the gaining of ready access to the interior 15 of the receptacle comprised in the device without separation of the parts of the device, for various purposes.

To the attainment of the foregoing the invention consists in the improvement as 20 hereinafter described and definitely claimed.

In the accompanying drawings, hereby made a part hereof:—

Figure 1 is a plan view showing my novel 25 vanity case in close state.

Fig. 2 is a plan view showing the vanity case in open state.

Fig. 3 is an enlarged diametrical section on line 3—3 of Fig. 1 illustrating the relative arrangement of the receptacle body and 30 the cover member complementary thereto when said cover member is in closed position.

Fig. 4 is an elevation of the hinge employed in the connection of the cover member 35 to the receptacle body.

Fig. 5 comprises detail views of the fastener members which are preferably included in the device.

Similar numerals of reference designate 40 corresponding parts in all of the views of the drawings.

Among other elements my novel vanity case or analogous device comprises a receptacle body 1, of pasteboard, and a cover member 2 also of pasteboard. The receptacle body 1 is circular in form, and the cover member 2 is flanged as indicated by 45 3 to take over the side wall of and tightly close the receptacle body.

A hinge 4 is employed for the permanent 50 connection of the cover member 2 to the receptacle body 1. The said hinge 4 comprises leaves 5 of thin sheet metal and a pintle 6; the leaves being equipped with barbs 7 adapted to be pushed through the side walls of 55 the body 1 and cover member 2 and bent

against the inner sides of said side walls. This mode of hinge connection is rendered feasible by the pasteboard character of the elements 1 and 2 and is economical in that 60 the hinge is connected of itself, and is, at the same time strong and durable. The receptacle body 1 may be utilized to contain face powder and a powder puff indicated by 65 8, or may be utilized as a purse for the carrying of coins or the like. When the receptacle body 1 is to be used to carry powder and a powder puff the cover member 2 will be equipped with a mirror 9, the said mirror 9 being retained in the cover member 70 10 through the medium of an annulus 10, held by frictional contact against the side wall or flange 3 of the cover member. When deemed expedient the cover member 2 may be detachably fastened in close position through the medium of the snap fastener members 11 and 12, best shown in Fig. 75 5. The fastener member 11 is formed of thin sheet metal, is equipped with a teat 13 and is also provided with barbs 14, designed 80 to be pressed through the side wall of the receptacle body and bent against the inner side thereof to strongly attach the member of itself to the receptacle body. The fastener member 12 is provided with barbs 15 85 for the connection thereof to the side wall or flange 3 of the cover member 2, and is also provided with a spring socket 16 complementary to the teat 13 and adapted to be pressed over and removed from the teat 90 13 by the exercise of a little stress.

Surrounding and attached by appropriate adhesive substance to the outer side of the receptacle body 1 is an annular fabric body 17 by which are carried a plurality of artificial leaves 18 which preferably simulate rose leaves. Manifestly the pasteboard character of the receptacle body 1 readily lends itself to the economical and strong adhesive connection of the said fabric body 17. 100 It will also be noted here that the fabric body 17 carries a stem 19 colored and embellished in simulation of a rose stem or the stem of any other flower.

In addition to the elements named my improvement includes an artificial flower 20 which is illustrated as simulating a wild rose but which may be made to simulate any other open flower without affecting my invention. The fabric portions 21 and 22 110 simulate the petals and the pollen, respectively, of the flower, and they are attached

to and carried by a fabric body 23 which rests in cap-like manner over the cover member 2 and is connected thereto by appropriate adhesive or other means compatible with 5 the purpose of my invention. The said body 23 is also made and colored to simulate the portion of a flower by which the petals are carried. I prefer for obvious reasons to employ adhesive for the connection 10 of the fabric flower body 23 to the cover member 2, and it will be readily understood that the pasteboard character of the cover member 2 readily lends said cover member to said mode of attachment.

15 It will be manifest from the foregoing that my novel device is adapted to be worn as an article of personal adornment on the corsage of a lady's dress; also, that when so worn the device presents the appearance of 20 nothing save a flower and a group of leaves on a common stem with the flower. When however, the wearer of the device desires to powder her nose or other portions of her face, the device may be readily removed 25 from the corsage and using the stem 19 as a handle, the device may be conveniently opened for the removal of the powder puff and may be held in proper position for the user to view her face or a portion thereof in 30 the mirror 9. Then after the completion of the toilet operation the powder puff may be replaced in the receptacle body 1, and the cover member may be closed, after which

the device may be restored to its position on the corsage to serve the ornamental function 35 alluded to.

While my novel device is designed primarily as a vanity case, it is clearly within the purview of my invention to utilize the receptacle body 1 as a mere receptacle for 40 money, street car tickets or tokens or other articles of value that it is desirable to safely carry in such manner that access may be readily gained thereto when occasion demands.

Having described my invention, what I claim and desire to secure by Letters-Patent, is:—

A device for personal wear comprising a receptacle body of pasteboard, a flanged 50 cover member of pasteboard, a hinge joining the receptacle body and the cover member and connected of itself to the walls thereof, a fabric body surrounding the receptacle body and connected by adhesive thereto and 55 provided with portions simulating leaves and with a portion simulating a flower stem, and a cap-like fabric body arranged over and connected by adhesive to the cover member and provided with portions simulating 60 the petals of a flower and other portions simulating the pollen of a flower; said cap-like body simulating the portion of a flower by which the petals are carried.

In testimony whereof I affix my signature, 65
MARGARET H. BROSNAN.
